UNITED STATES PATENT OFFICE.

GEORGE A. COLTON, OF PHENIX, NEW YORK.

FOOD-CUTTER.

SPECIFICATION forming part of Letters Patent No. 760,779, dated May 24, 1904.

Application filed August 24, 1903. Serial No. 170,591. (No model.)

To all whom it may concern:

Be it known that I, GEORGE A. COLTON, a citizen of the United States, residing at Phenix, in the county of Oswego, State of New York, have invented certain new and useful Improvements in Food-Cutters, of which the following is a specification, reference being had therein to the accompanying drawings.

This invention relates to a food-cutter, and particularly to a structure embodying a cylinder having a feed-screw therein and a cutting-disk at the discharge end of said screw.

The invention has for an object to improve the construction of screw so as to prevent the feeding of material away from the axis thereof and also to improve the construction of the rotatable cutting-disk and a fixed plate co-operating therewith, so as to secure the most efficient results and a cutting action upon all portions of the disk.

A further object of the invention is to improve the construction of the handle, by which it may be removed when desired and the feed-screw disconnected therefrom at any time.

Other and further objects and advantages of the invention will be hereinafter set forth and the novel features thereof defined by the appended claims.

In the drawings, Figure 1 is a central vertical section of the invention with the clamping portion thereof in elevation. Fig. 2 is an end elevation at the handle end of the device. Fig. 3 is a detail vertical section of a portion of the feed-screw. Fig. 4 is a plan of the fixed disk. Fig. 5 is a perspective of the movable cutting-disk, and Fig. 6 is a central vertical section therethrough.

Like letters of reference refer to like parts in the several figures of the drawings.

The letter A designates a cylinder or body of the cutter, which is provided at its upper end with the usual feed-hopper A' and at its lower portion with a depending arm or standard A², having any desired form of securing means connected therewith—for instance, a fixed lug A³, extending laterally from the standard A² and co-operating with an adjustable clamping-screw A⁴, carried by the lower end A⁵ of the standard, said screw being provided with an operating-handle A⁶ of any con-

struction. For convenience of construction the casing of the cutter is formed of two parts and secured together by rivets or bolts in the usual manner. The interior of the cylinder A is provided with ribs A⁷, spirally disposed upon the walls, as usual in this art, and at one end a bearing A⁸ is provided and adapted to receive the axis B' of the feed-screw B. The threads of this screw are disposed in the usual manner; but instead of terminating in a straight edge, as heretofore in this art, they are provided upon their peripheries with flanged or laterally-extending portions B², which are formed parallel to the axis of the screw and upon the advancing face with the curved surfaces B³, the object thereof being to feed the material carried by the screw both forwardly and downwardly toward the axis thereof. When the straight-edge screw is used, the material is thrown toward the periphery of the screw and dragged or mashed between the same and the ribs of the cylinder, and the cutting action is largely confined to the outer edge of the disk.

At the discharge end of the feed-screw a fixed plate C, provided with suitable apertures C' for the feed of material therethrough, is secured in position in any desired manner—for instance, by means of a radially-extending lug C², adapted to enter a suitable socket or recess A⁹ in the casing, and this plate is provided with a central aperture C³, within which the bearing B⁴ of the feed-screw is disposed. The shaft of this screw beyond the bearing B⁴ is provided with an angular portion B⁵ and terminates in a threaded end B⁶. This angular portion is adapted to connect the cutting-disk D to the shaft of the screw for rotation therewith, and for the purpose of securing the maximum extent of contact with the walls of this angular portion the central portion of the disk D is struck up, as shown at D', forming an arched portion which prevents a lateral or wobbling motion of the disk and also stiffens the point of connection, so as to resist the strain due to the cutting action. The cutting-disk D is provided with any suitable number of apertures D² and adapted to be formed of steel suitably tempered, these apertures being tapered inward, so as to secure a free dis-

charge of cut material therefrom. The arched portion D' forms a curved face, in contact with which the securing-nut E is adapted to bear, this nut being provided with a conically-recessed portion E' in order to secure a large surface in contact with the arched portion D' of the cutting-disk and thus more firmly hold it in its adjusted position upon the shaft of the feed-screw.

- 10 For the purpose of removably securing the handle F to the shaft or axis of the feed-screw the latter is provided with an extended squared portion B', adapted to fit a similar recess F' at the upper end of the handle, while the inner 15 face of the handle is provided with a recessed portion F' to receive the bearing A⁸, extending outwardly from the cylinder, and this recessed portion is provided upon one face with a peripherally-extending segmental rib F³.
- 20 Coöoperating with this rib and disposed upon the end of the cylinder portion of the cutter are lugs F⁴, behind which the rib is adapted to fit and travel in the ordinary operation of the handle, so as to prevent an accidental 25 engagement thereof. When it is desired to remove the handle, the cutting-disk and plate, together with the feed-screw, are removed from the cylinder and the handle then turned to bring the segmental flange out of contact 30 with one of the lugs, so that by a lateral movement thereof it may be removed from the remaining lug, thus permitting all parts of the cutter to be separately cleaned.

In the operation of the invention it will be seen that the material fed into the hopper is carried by the feed-screw outward and forced through the fixed plate at the discharge end of said screw, where the portions projected through said plate are engaged by the cutting-disk and separated by a shearing action, so as to secure a perfectly clean cutting of the material without any chopping, mashing, or mangling thereof. It will also be apparent that by removing the clamping-nut the cutting-disk may be removed and replaced by a different size, while the fixed plate coöperating with said disk is capable of instant removal and replacement by lifting the same from its securing-socket. When these are removed, the feed-screw can be drawn directly outward and the handle separated from the casing by an upward movement thereof. The parts may be assembled by a reverse operation and are so simple in construction that they are capable of operation and assemblage by any person. The construction of the feed-screw having the laterally-disposed flanges upon its blades exerts a forcing power at nearly a right angle to the axis of the screw, so that the material which is ordinarily carried outward from the axis of the screw and fed only to the outer openings of the cutter is carried forward in an even body, thus securing an equal cutting action upon all the 65 surfaces of the disk. The formation of this

disk is also an important improvement in that it permits the same being formed of cheap material in which the cutting-apertures may be punched and the material then tempered, so as to secure the most efficient results in the 70 wear and action thereof.

It will be obvious that changes may be made in the details of construction and configuration without departing from the spirit of the invention as defined by the appended claims. 75

Having described my invention and set forth its merits, what I claim, and desire to secure by Letters Patent, is—

1. In a food-cutter, a cylinder provided with a feed-hopper at one end, cutting means at 80 the discharge end of the cylinder, and a feed-screw extending from the hopper to the cutting means and having the periphery of its blades extended parallel to the axis of the screw throughout its length and toward the 85 discharge end thereof.

2. In a food-cutter, a feed-casing having solid walls, a fixed plate and rotatable cutter at the delivery end thereof, and a feed-screw comprising spirally-disposed blades having 90 their periphery extended parallel with the axis of the screw throughout its length within the casing and toward the discharge end thereof.

3. In a food-cutter, a cylinder, a feed-screw, 95 a fixed apertured plate secured in position by said cylinder, an apertured cutting-disk having an angular central aperture with arched walls to engage squared faces upon the shaft of said screw, and a nut for securing said disk 100 in position.

4. In a food-cutter, a cylinder, a feed-screw, a fixed apertured plate secured in position by said cylinder, an apertured cutting-disk having an angular central aperture with arched 105 walls to engage squared faces upon the shaft of said screw, and a nut having a concaved recess adapted to seat upon the arched portions of said disks.

5. In a food-cutter, a cylinder, a feed-screw having the periphery of its blades extended laterally throughout its length, a fixed apertured plate secured in position by said cylinder, an apertured cutting-disk having an angular central aperture with arched walls to engage squared faces upon the shaft of said screw, a nut having a concaved recess adapted to seat upon the arched portions of said disks, and a radial projection from said plate adapted to enter a socket in said cylinder. 115 120

6. In a food-cutter, a cylinder, a feed-screw, a fixed apertured plate secured in position by said cylinder, an apertured cutting-disk having an angular central aperture with arched walls to engage squared faces upon the shaft of said screw, a nut having a concaved recess adapted to seat upon the arched portions of said disks, a radial projection from said plate adapted to enter a socket in said cylinder, a bearing portion at the feed end of the cylin- 125 130

der for the shaft of said screw, an angular end to said shaft, a handle disposed upon said end and provided with a recess to receive said bearing portion, a segmental flange upon said handle, and a lug carried by the body of the casing and disposed over said flange.

5 7. In a food-cutter, a cutting-disk comprising a plate having tapered apertures therein and a central angular aperture, having the walls thereof arched at opposite sides of the central aperture.

10 8. In a food-cutter, a casing, a shaft mounted therein, a handle removably connected to said shaft by an angular socket at one end, a segmental flange extended from said handle concentric to said shaft, and securing-lugs extended from the face of the casing at opposite points beyond the plane of rotation of said flange.

9. In a food-cutter, a casing, a shaft mounted in a bearing extended therefrom, a handle removably connected to said shaft at one end and recessed to receive said bearing, a segmental flange extended from said handle, oppositely-disposed securing-lugs extended from the face of the casing beyond the plane of rotation of said flange, a feed-screw upon said shaft, a cutting-disk secured to said shaft at the discharge end of the casing, and a wing-nut for retaining said disk in contact with a fixed portion of the casing.

In testimony whereof I affix my signature in presence of two witnesses.

GEORGE A. COLTON.
